UNITED STATES PATENT OFFICE.

WILLIAM C. LIPSCOMB, OF CROCKETT, TEXAS.

LOADING APPARATUS.

No. 889,699.

Specification of Letters Patent.

Patented June 2, 1908.

Application filed September 13, 1907. Serial No. 392,654.

To all whom it may concern:

Be it known that I, WILLIAM C. LIPSCOMB, a citizen of the United States, residing at Crockett, in the county of Houston and 5 State of Texas, have invented new and useful Improvements in Loading Apparatus, of which the following is a specification.

My present invention relates to improvements in devices for loading material of various kinds either in bulk or in other conditions preparatory to its handling for the purpose of transferring it from one point to another, and it has for its object primarily to provide a loader of this character embodying 15 flexible load engaging members which are composed of jointed sections that permit the relative opening and closing of the members in order that they may readily close upon the material to be handled, and when released 20 they will immediately straighten and permit the dumping and discharge of the material being handled.

Another object of the invention is to provide devices for flexing the sections for the 25 purpose of effecting the opening and closing movements of the members.

To these and other ends, the invention consists in certain improvements, and combinations and arrangements of parts, all as 30 will be hereinafter more fully described, the novel features being pointed out particularly in the claims at the end of the specification.

In the drawings—Figure 1 is an end elevation of a loader constructed in accordance 35 with the present invention, the load engaging members being shown in open position; Fig. 2 is a view similar to Fig. 1 showing the load engaging members in closed relation; Fig. 3 is a side elevation of the loader shown in Fig. 40 1, a portion thereof being shown in section; Fig. 4 is a detail view of one of the load engaging members detached from the loader; Fig. 5 is a sectional view of the load engaging members shown in Fig. 4; Fig. 6 represents 45 a vertical section through one of the load engaging members; Fig. 7 represents a section 50 through the axes of the joints connecting the several sections to one of the flexible members; Fig. 8 is a perspective view of one of the sections detached; and Fig. 9 is a perspective view of a section of the chain which serves to link together the several sections of each member.

Similar parts are designated by the same 55 reference characters in the several figures.

Loading devices constructed in accord-

ance with my present invention, are capable of being constructed in various forms in order that they may be adapted for use in the handling of loose material, such as dirt 60 or coal, or the like, and they may be also modified to adapt them for use in the handling of solid material in the form of lumps or blocks, such as coal, stone or the like.

I have shown the invention in its present 65 embodiment as applied to a loader that is adapted for use generally in connection with crane or other hoisting device for the purpose of handling material in bulk, the loader in this instance comprising generally a supporting frame 1 having the load engaging members arranged at the opposite sides thereof, the frame being provided with means for attaching it to a crane or other hoisting or transferring device. These load 70 engaging members 2 and 3 are each composed in the present instance of a pair of flexible arms 4 and 5, the latter embodying sets of jointed sections 6 which are so connected 75 that they permit flexing of the arms for the purpose of accomplishing the opening and closing movements of the load engaging members. The uppermost section of each arm is rigidly attached to the supporting frame by means of straps 7, and the several 80 sections composing each arm are united by a link construction which permits the requisite pivotal movements thereof to effect the flexing of the arm. Any suitable link construction may be employed for this purpose, 85 that shown in the present instance embodying a chain comprising two sets of links 8 and 9 which are arranged at opposite sides of the sections and extend longitudinally of the arm, and a set of connecting bolts or equivalent 90 devices 10 which join the links of the two sets and pass between the joints of the sections. These connecting bolts are preferably surrounded by sleeves 11, and the latter rest in segmental grooves 12 formed in the proximate 95 sides of the several sections. In order to permit relative pivotal movement of the sections about the connecting bolts as axes, the proximate surfaces of the several sections are beveled or otherwise formed to form clear- 100 ance spaces 13, these spaces being so constructed that the material cannot collect therein to such an extent as to interfere with the flexing of the arms. The lowermost section 14 of each arm is preferably pointed and 105 directed inwardly as shown in order to facilitate its entrance into the material to be

loaded, and the several arms are of such a length that they will engage or rest in close proximity to one another when the load engaging members are in closed position.

Any suitable means may be employed for operating the arms to open and close them, a pair of flexible tension devices 15 and 16 being employed in the present instance which may be composed of cords, wires or chains, and they extend through sets of openings 17 and 18, extending through the several sections at opposite sides of the connecting bolts which serve as axes of movement, and the lower ends of these flexible members are anchored to the lowermost section 14, as at 19 and 20. With the tension members so connected, a tension on one of them would obviously cause the several sections to rock about the connecting bolts as axes, the arm being thereby flexed so as to perform either an opening or a closing movement. In the present instance the tension members of the two arms at one end of the loader are wound upon a pair of differential drums 21 and 22, the outer members 17 being wound upon the larger drum, while the inner members 18 are connected to the smaller drums. The loader shown is adapted to handle a considerable quantity of material at each load, and for this reason each load engaging member is composed of a pair of flexible arms, the arms being connected by cross pieces 23 which are attached to the individual sections and provide a lining 35 which serves as a bottom for the loader when the members are in closed position, and the lowermost sections 14 of each member are connected by a blade 24, the lower edges of these blades being preferably sharpened or pointed to enable them to readily dislodge the load and thereby facilitate its entrance between the members. In handling loose material, such as earth, sand or the like, it is preferable to provide end pieces 25 which are secured to the opposite ends of the supporting frame and have an outline corresponding substantially to the curvature of the co-operating members when the latter are in closed position, these end pieces preventing spilling of the material between the ends of the members.

In practice, the loading device is lowered while the members 2 and 3 are in open or vertical position as shown in Fig. 1, the drums 55 controlling the flexible operating elements being rotated in an appropriate direction to relieve the tension on the inner members 18, the formation of the lower ends of these members enabling them to enter the material to be loaded. While the members are thus embedded, the drums controlling the flexible operating members are rotated to produce a tension on the inner flexible members 18, and this will cause the lowermost sections 14 of 60 the respective members to turn inwardly,

and the consequent shortening of these inner flexible members will flex the members until they assume a closed position, as shown in Fig. 2. In operating the loader from a crane, it may be advantageous to operate the load 75 engaging members from a distant point, and this may be accomplished by a chain or other means operatively connected to the drums, a pair of sprocket wheels 26 being provided for that purpose in the present instance. 75

The gripping members in the present embodiment co-operate to form gates which open and close to load and discharge the material, the cross pieces connecting the jointed or articulated arms serving to lengthen the gates 80 according to the desired capacity of the loader. Obviously, in using relatively long gates, one or more intermediate articulated arms may be provided for the purpose of reinforcing the cross pieces, and in some cases 85 such as in the handling of lumpy coal, blocks of stone and similar shapes, it may be advantageous to omit the cross pieces connecting the arms and to so arrange the articulated arms that they directly engage beneath and 90 at the sides of the object to be handled, the arms being grouped in a set of two or more connected for simultaneous operation, and in such constructions, the arms may be mounted to operate in various planes relatively to 95 one another so that they may co-operate at two or more sides of the object and thereby insure security of the hold they obtain.

By omitting the end sections of the receptacle, the device may be used advantageously 100 for the handling and loading of corn stalks and other relatively long objects, and, moreover, it will be clear that a loading device embodying the general features of the invention may be made, either with or without modification, so as to adapt it for use in loading, hoisting, transferring and dumping materials of various kinds and in different conditions. Moreover, in some constructions, it may be advantageous to so joint the several sections 105 in order to permit flexing of each arm or sections in several directions in addition to the plane of movement in opening and closing, universal joints between the sections permitting such movements and in those cases a 110 suitable additional number of traction or operating cords or chains would be employed for the purpose of effecting the desired movements. In this way, a wiggling motion may be imparted to the several arms that will 115 facilitate their introduction into lumpy substances, such as coal, ore, stone and the like, the connecting cross pieces and the knives or sharpened edges in those cases being preferably omitted. 120

It will be understood, of course, that loading and dumping devices constructed in accordance with the present invention may be adapted for use on aerial cables, or they may be mounted on wheels for use as dumping 125 130

wagons, and in fact they are capable of use in various connections wherein it is desirable to transport material from one point to another.

I claim as my invention—

- 5 1. A loader embodying a pair of oppositely mounted articulated arms capable of being flexed to engage and disengage a load.
- 10 2. A loader embodying articulated arms oppositely mounted for movement in substantially the same plane and connected for simultaneous flexing action for loading.
- 15 3. A loader embodying coöperatively arranged arms composed of jointed sections, and devices for flexing the arms to proximate and separate their free ends to receive and discharge a load.
- 20 4. A loader embodying coöperatively arranged arms capable of a flexing action for loading and discharging and having flexible tension members connected thereto for flexing them, and drums coöperating with the tension members to wind one member and unwind another member for flexing the arms.
- 25 5. A loader embodying a pair of coöperatively arranged arms composed of jointed sections, a pair of flexible operating members for each arm, and drums of differential diameters coöperating with the respective operating members of each arm.
- 30 6. A flexible arm for loaders of the character described composed of a set of sections pivotally connected to permit flexing of the arm, and a pair of flexible operating members extending longitudinally of the arm at opposite sides of the pivots of the sections.
- 35 7. An arm for loaders of the character described composed of a set of pivotally connected sections having longitudinally extending openings at opposite sides of the pivots, and flexible operating members ex-

tending through the said openings and having their ends attached to the section at one end of the arm.

8. A loader embodying a supporting frame, and a pair of coöperatively arranged articulated members adapted to open and close the bottom of the frame by a relative flexing movement of the members, and means carried by the frame for flexing the members.

9. An arm for loaders of the character described embodying a set of sections having channels in their proximate faces, pivots engaging in the channels between adjacent sections, and links extending longitudinally of the arm and connected to the pivots.

10. A loader comprising a supporting frame, coöperatively arranged load engaging members mounted thereon, each embodying a plurality of articulated arms, means for flexing the arms, coöperating knife blades at the lower ends of the arms, and cross pieces connecting the arms and forming a bottom for the frame.

11. In an apparatus for handling materials for loading and dumping the same, the combination with a suitable supporting frame, of coöperatively arranged members jointed to permit flexing thereof to open and close the bottom of the frame, and pivoted on opposite sides of the latter and devices operable to proximate and separate the free ends of the members for effecting the opening and closing of the members.

In testimony whereof I have hereunto set my hand in presence of two subscribing witnesses.

WILLIAM C. LIPSCOMB.
